UNITED STATES PATENT OFFICE.

WILLIAM STUCK AND WILLIAM F. BOSDORFER, OF INDIANAPOLIS, INDIANA, ASSIGNORS TO
JOHN C. McCLOSKEY, OF INDIANAPOLIS, INDIANA.

HOLDER FOR LACE CURTAINS AND WINDOW-SHADES.

No. 905,949.

Specification of Letters Patent.

Patented Dec. 8, 1908.

Application filed March 6, 1908. Serial No. 419,594.

To all whom it may concern:-

Be it known that we, WILLIAM STUCK and WILLIAM F. BOSDORFER, citizens of the United States, residing at Indianapolis, in 5 the county of Marion and State of Indiana, have invented certain new and useful Improvements in Holders for Lace Curtains and Window-Shades, of which the following is a specification.

10 This invention relates to a combined window shade and curtain support; and the object of the invention is to provide a single means to be attached to the window casing on which the shade and curtain brackets are attached; the arrangement of parts being such that the brackets for both the shades and curtains can be laterally adjusted or separated to accommodate windows of different widths.

15 A further object of the invention consists in providing a single means for attaching shade and curtain brackets whereby adjustment of the curtain retaining brackets is made possible so that the curtains may be 20 hung the desired distance in advance of the shades.

25 We accomplish the objects of our invention by means of a device illustrated in the accompanying drawings, forming a part 30 hereof, in which—

Figure 1 is a perspective view of a combined shade and curtain support. Fig. 2 is a longitudinal sectional view of one end of the supporting device, on an enlarged scale, on 35 the line A—A in Fig. 1. Fig. 3 is an end view of the supporting device, on an enlarged scale.

40 In the drawings, 1 represents the supporting member to which the shade and curtain brackets are attached, and consists, primarily, of a thin strip composed either of wood or metal. The member 1 is attached to the horizontal portion of the casing above the window by means of screws that pass through 45 the screw-holes 2, 2. The member 1 may be finished to harmonize with the interior wood-work of the room in which it is employed. The member 1 is provided at each end with a pair of parallel grooves 4 and 5 which are cut 50 into the outer surface thereof. The grooves 4 provide ways or guides to receive and retain the shade brackets, while the grooves 5 perform a similar function for the curtain brackets.

55 7 represents the shade brackets which are

similar to the well known Hartshorn shade bracket, except that they are provided with extremely long right angle extending feet 8. The feet 8 snugly fit the grooves 4 in cross section and each are provided with a longitudinally extending slot 9, through which the bolts 10 extend. The bolts 10 are firmly held within the member 1, while the projecting ends are provided with the thumb-nuts, 12, whereby the adjustment and locking of 60 the shade brackets 7 is made possible.

65 The curtain brackets consist of two members 16 and 17, arranged against each other in an adjustable manner. The base members 16 of these brackets are L-shaped, thereby providing right angularly extending feet 19, similar to the feet 8 on the shade brackets 7, and fit within the grooves 5 in the same manner as do the brackets 7 in the grooves 4. The feet 19 are each provided 70 with a longitudinal slot 20, through which the bolts 21 pass and by means of the thumb-nuts 22 the brackets may be adjusted and then secured in the desired position upon the supporting member 1. The member 17 of 75 the curtain brackets provide the means for lengthening them so that the curtains may be made to hang clear of the shades. The adjustability of the curtain brackets is attained by providing each of the base members 16 with a slot 25. Wing-nuts 26 pass 80 through the slots 25 and into the members 17 so that the two may be secured together when the proper adjustment has been made. In order to prevent the projecting ends of the 85 members 17 from drooping when the curtains have been placed into position, we provide these members with the longitudinal slots 28, adapted to receive the lugs 29 which are formed on the bodies of the base members 16. These lugs may have their ends flattened to form the heads 30 so as to prevent accidental separation of the members 16 and 17. The members 17 of the curtain brackets terminate at their outer ends in the 90 hooks 31 which receive the curtain poles, not shown.

95 Having thus fully described our said invention, what we desire to secure by Letters Patent, is—

100 A combined shade and curtain support comprising a base-plate provided at each end with a plurality of parallel grooves, a pair of L-shaped shade retaining brackets slidingly arranged within the lower grooves in said 105 110

base-plate, said brackets being provided with longitudinal slots, clamping means for securing said brackets to the base plate, a pair of L-shaped curtain bracket base members slid-
5 ingly arranged in the upper grooves in said base-plate, said curtain brackets being pro-
vided in their base portions with longitudinal slots, clamping means for securing said curtain bracket base members to the base-plate,
10 the projecting portions of said base members being provided with longitudinal slots, exten-
sion members for the curtain bracket base members provided with longitudinal slots,
said members adapted to lie against the pro-
15 jecting portions of the curtain bracket base

members, means on the curtain bracket base members adapted to engage the extension members, and clamping devices adapted to secure the extension members and the curtain bracket base members together.

20

In witness whereof, we have hereunto set our hands and seals at Indianapolis, Indiana, this 6th day of January, A. D. one thousand nine hundred and eight.

WILLIAM STUCK. [L. S.]
